UNITED STATES PATENT OFFICE.

MARKS SAMUELS, OF NEW YORK, N. Y., ASSIGNOR OF ONE-HALF TO
ANNIE ABRAMS, OF SAME PLACE.

BASE OR SUPPORT FOR FURNITURE.

SPECIFICATION forming part of Letters Patent No. 373,311, dated November 15, 1887.

Application filed March 31, 1887. Serial No. 233,165. (No model.)

To all whom it may concern:

Be it known that I, MARKS SAMUELS, a citizen of the United States, residing at New York, in the county and State of New York, have invented new and useful Improvements in Bases or Supports for Furniture and other Articles, of which the following is a specification.

This invention relates to a base or support for furniture and other articles, whereby said articles are enabled to be easily turned or faced about while said base or support remains fixed or stationary.

This invention is set forth in the following specification and claims, and illustrated in the accompanying drawings, in which—

Figure 1 is a section in the plane xx , Fig. 2. Fig. 2 is a section in the plane yy , Fig. 1. Fig. 3 is a section in the plane zz , Fig. 1. Fig. 4 is a section in the plane vv , Fig. 2. Fig. 5 is a plan view of a modified form of base. Fig. 6 is a section in the plane ww , Fig. 5.

Similar letters indicate corresponding parts.

In the drawings, the letter A indicates a base or support. A frame or movable portion, B, is adapted to move in suitable ways or guides in the base A. The movable portion B is provided with a pin or pivot, C, engaging a bottom side or portion, D, of an object, such as an article of furniture.

The article shown in the drawings consists of a closet, E, and a folding bed, F, adapted to open or close by swinging about a joint or hinges, G. To steady the article a support—such as a disk, H—is placed about the pivot C and between the base A and the bottom D of the supported article.

The bottom or portion D of the article is provided with a pin or pivot, I, having a portion, K, adapted to travel along a track or way, L. The way L may be made in the shape of a track on the base A, as seen in Figs. 3 and 4, or in the shape of a groove in the base A, as seen in Figs. 5 and 6. The portion K is shaped to engage the way L, as seen in Figs. 4 and 6.

When the article is turned about the pin C in the direction of arrow 1, Fig. 2, the motion of the bottom or side D, turning about the pin C, carries the guide or portion K from the position shown in full lines in Fig. 3 to the position indicated in dotted lines in said figure. The frame B and disk C are also carried by

said motion to the positions shown in Fig. 3 in dotted lines.

In Fig. 3 the dotted lines show the position of the parts after the part D has been given a quarter-turn, or revolved through an arc of ninety degrees. The folding bed F has thereby been moved, so that if said folding bed in Fig. 1 had faced a wall said folding bed would now be in a position to be opened about its pivots or hinge alongside of said wall. Of course, if desired, the revolution of the portion D may be continued through an arc of one hundred and eighty degrees from the position shown in Fig. 1. If the portion D is moved through an arc of one hundred and eighty degrees, the guide or portion K, which in Fig. 3 is near one extremity of the way or track L, will be brought near to the other extremity of way L. If the portion D is moved through an arc of ninety degrees, the action of the way L and portion K will be such as to move the frame B partly out of the base A, as seen in Fig. 3 in dotted lines. This motion will give the article room to turn in case the base A is near the wall of a room. When the portion D is moved back to the position shown in Fig. 3 in full lines, the action of the way L and portion K will carry the frame B back to the position shown in full lines in Fig. 3. To secure this motion of the frame B the track or way L is cam-shaped, as seen in Figs. 3 and 5.

If desired, the free end of the frame B may be provided with rollers for supporting said free end, and which rollers will allow the frame B to travel easily back and forth.

What I claim as new, and desire to secure by Letters Patent, is—

1. The combination, with a base, A, having a cam-shaped way, L, of a movable frame, B, and an object or article, D, connected to the frame B, and provided with a guide, K, adapted to engage the way L, substantially as set forth.

2. The combination, with a base, A, having a cam-shaped way, L, of a movable frame, B, and an object or article, D, connected to the frame B, and provided with a guide, K, adapted to engage the way L, and a disk or support, H, interposed between the frame B and the object D, substantially as set forth.

3. The combination, with a movable frame, B, and a base, A, having a cam-shaped way,

L, and provided with guides for the reception of the movable frame B, of an object or article, D, connected to the frame B, and provided with a guide, K, adapted to engage the way L, substantially as set forth.

4. The combination, with a base, A, having a cam-shaped way, L, of a movable frame, B, and an object or article, D, made to revolve or swivel on the frame B, and provided with a

guide, K, adapted to engage the way L, substantially as set forth.

In testimony whereof I have hereunto set my hand and seal in the presence of two subscribing witnesses.
